UNITED STATES PATENT OFFICE

HENRY ROBINSON, OF NEW YORK, N. Y.

COMBINATION CHUTE AND CHAMBER CLOSURE

Application filed February 17, 1930. Serial No. 429,157.

My invention relates to a discharge means or combination chute and chamber closure for use on vegetable paring and washing machines or the equivalent, to guide the vegetables or material downwardly into a receptacle, as the same emerge from the machine and to prevent insertion of the hands of the operator or others into the machine and into contact with the rapidly moving mechanism therein.

An important object is to provide a means or frame which will constitute a barrier or abutment for laterally discharged vegetables or other materials, especially when forcibly or centrifugally discharged, to intercept the movement thereof so that the same will not be scattered broadcast, but will be caused to travel downwardly into a collecting receptacle.

Another important object is to provide a construction wherein the frame or chute is adapted to be substantially closed at the top by the door of the discharge opening in the cylinder or chamber so that the vegetables or materials will be confined so that they must fall into the receptacle and also that the operator or others, cannot thrust their hands into the machine and risk injury thereto by the rapidly rotating mechanism therein.

A further object is to provide a reinforcing member on the frame or chute which contacts with the fastening means of the aforesaid door, so that the latter may be constantly urged to closed position and compensation made as the gasket thereof wears.

Another aim is to provide a fastening handle for the said door which is forwardly offset so as to facilitate manual engagement and holding especially when the said door is in chute-closing position.

Various additional objects and advantages will become apparent from a consideration of the description following taken in connection with accompanying drawings, illustrating, by way of example, one practical embodiment of the invention.

In said drawings:—

Figure 1 is a perspective view of a vegetable paring and washing machine embody-

ing the invention, the chamber door or closure being in closed position;

Figure 2 is an enlarged detail sectional view taken vertically and diametrically of the chamber through the frame or chute and the door of the chamber, the latter being shown closed in full lines and in chute-closing position in dotted lines;

Figure 3 is a perspective view of the said vegetable paring and washing machine in a different position from Figure 1, the said door being in chute-closing position, and

Figure 4 is a plan view of the frame or chute alone.

Referring specifically to the drawings, wherein like reference characters designate like or similar parts throughout the different views, A designates a vegetable paring and washing machine of the general type disclosed in my pending applications for Letters Patent, Serial Numbers 87,472 and 87,473, both filed August 21, 1929, although it is obvious that no limitation is to be implied in this connection, since the improvement may be used in connection with other apparatus within the scope of the invention as defined in appended claims.

Insofar as it is necessary to describe the machine for an understanding of the present improvements, 10 designates the chamber wherein the vegetables or materials are pared or washed through the medium of a suitably rotated agitating element 11. Said chamber has a hinged lid or cover 9 and a lateral discharge opening 12 through its side wall which is normally closed by a door or closure 13 preferably having a gasket at 14 whereby it may fit the wall of the chamber so that water or steam cannot escape. Said closure 13 is hinged at its top at 15 by a horizontally disposed pin mounted in lugs 16 and 16' on the chamber and door, respectively, permitting the door or closure to be opened by swinging the same upwardly and the latter reinforcing the closure.

In connection with the discharge opening 12, a frame or chute 17 is employed which may be a casting or otherwise made in one or more parts, as preferred. Such chute 17 is generally of U-shape in plan as shown in Fig-

ure 4 and may have lateral attaching flanges 18 at its free edges which are riveted, welded or otherwise attached at 19 to the chamber. Thus such chute is open at both top and bottom. In addition, a bar or web 20, preferably integral with the frame or chute 17 to reinforce the same, spans the side walls thereof at the bottom, having a rim or downwardly extending flange 21 intimately fitting the exterior wall of the chamber so that in combination with the flanges 18 no leakage can occur through the joint of the chute and chamber.

Said web or bar 20 has a slot 22 there-through, one side wall 22' of which is inclined or cam shaped. The door or closure 13 is adapted to be manipulated for opening or closing by means of a lever or handle 23 pivoted thereto on a horizontal axis 23', the handle portion 24 being offset or angularly disposed and the other end 25 serving as a latch which is adapted to enter the slot 22, and due to the cam wall 22' of the latter, enabling progressive tightening of the door or closure, especially such as becomes necessary incidental to the wear on the gasket 14. The edge of said wall is preferably tapered as shown, to aid in easy operation of the lever 23. Said slot at the opposite wall, has a depending lip 20' to reinforce the bar and guide the lever.

A pin 29 is carried by lever 23 and is confined between lugs 16' and engageable therewith to limit the movement of such lever in opposite directions.

The machine shown is elevated or supported by legs 26 and a standard 27 whereby the chute is correspondingly elevated or raised above the floor or support. This arrangement accommodates any type of receptacle as at 28 removably arranged below and in line with the chute so that the latter may discharge therein.

When the machine is in operation, the vegetables or materials are pared or washed by the member 11 and coating parts, as disclosed in the aforesaid applications, but cannot escape therefrom through the opening 12 as the latter is normally closed by door 13 and latched in that position by the engagement of lever portion 25 in slot 22. The vegetables or materials are adapted to be discharged by centrifugal force by the member 11 through opening 12 when the door 13 is open or raised as in full lines in Figures 3 and dotted lines in Figure 2. When said door is raised, it is impossible for anyone to insert his hands into the machine through opening 12 and risk injury thereto, by contact with the rapidly rotating element 11. The chute 17 also arrests any scattering of the materials, confining the same and causing them to fall downwardly into the receptacle 28. At the same time, upward escape of materials is prevented by the door 13 which thus performs a further function of closing the chute 17 at the top.

The angle or deflection of the handle 24 greatly aids in engaging and manipulating the lever 23 and closure 13.

It will be noted that the chute does not present any crevices or portions which will clog 70 with material and be difficult to remove or clean and that the discharge feature may be kept sanitary at all times.

Further, it will be noted that the web or bar 20 not only reinforces the chute, but it 75 provides an exceedingly strong means for coacting with the lever 23 in applying the requisite pressure with safety against breakage strains on the door and associated parts.

I claim as my invention:—

1. In a machine of the class described, a chamber having a discharge opening, a chute on the exterior of the chamber about said opening for engagement by material discharged therethrough to confine the same so 85 that it will fall downwardly from the chute, a closure for said opening hinged at its top to the chamber, said closure being adapted to substantially close the top of the chute in its open position, an operating lever pivoted 90 to said closure, lugs on said closure, and a pin on the lever confined between the lugs and engageable therewith to limit movement of the lever in opposite directions.

2. In a machine of the class described, a chamber having a discharge opening, a chute on the exterior of the chamber about said opening substantially open at the bottom, a bar on said chute across said bottom adjacent the chamber provided with a slot, a closure for said opening, and a fastening member on the closure engageable in said slot.

3. In a machine of the class described, a chamber having a discharge opening, a chute on the exterior of the chamber about said opening and open at top and bottom, a bar on said chute across the bottom adjacent the chamber, a closure for said opening adapted in open position to substantially close the chute at the top, and a fastening means on said closure having fastening engagement with said bar.

4. In a machine of the class described, a chute comprising a vertically disposed body generally of U-shape, a bar spanning the chute adjacent the bottom and open side thereof, said bar having a portion interengageable by a closure fastening and on its surface within the chute being substantially unobstructed.

5. In a machine of the class described, a chute comprising a vertically disposed body generally of U-shape, a bar spanning the chute adjacent the bottom and open side thereof, said bar having means to coat with a door fastening and having a depending rim at said open side.

6. In a machine of the class described, a chute comprising a vertically disposed body generally of U-shape, a bar spanning the chute 130

adjacent the bottom and open side thereof to reinforce the same, said bar having a slot to coact with a door fastening, and a depending rib on the bar at one side of the slot.

- 5 7. In a machine of the class described, a chamber having a discharge opening, a chute on the exterior of the chamber about said opening substantially open at the bottom, a bar on said chute across said bottom adjacent
10 the chamber, the surface of the bar within the chamber being substantially unobstructed, a closure for said opening, and a fastening means on the closure interengageable with said bar.
- 15 In testimony whereof I have affixed my signature.

HENRY ROBINSON.
